UNITED STATES PATENT OFFICE.

HENRY C. KARLSON, OF HASBROUCK HEIGHTS, NEW JERSEY, ASSIGNOR TO V. VIVAUDOU, INC., OF NEW YORK, N. Y., A CORPORATION OF DELAWARE.

POWDER DISPENSER.

Application filed July 11, 1924, Serial No. 725,489. Renewed September 29, 1925.

- This invention relates to receptacles in general and it pertains more particularly to the species used for the distribution of powder.
- 5 One object of the invention is to produce a nonrefillable article of the kind described, adapted to be removably inserted into an existing, portable vanity case, to take the place of the ordinary compact.
- 10 Another object is the production of an article of the class specified which if pried open for re-filling, will become unfit for continued use.
- 15 A further object is to provide an article of the character mentioned, capable of being manufactured entirely by punch-press operations, on the order of tin-cans, and from low priced materials, so as to permit the same to be discarded, when emptied of its 20 contents.
- 25 Still another object consists in producing an article of the class set forth, wherein means embodied in a relatively unyielding internal rim or ledge render the later sufficiently resilient and pliable to conform, to the coacting surface of a closure member, and make a tight joint therewith, dispensing as well with seats of soft texture intermediate the before named ledge and member.
- 30 A still further object resides in providing an article of the type referred to, comprising but few plain parts, exclusively of metal; readily produced, charged and assembled by the least expensive labor; besides reliable 35 and convenient in operation.
- Other objects and advantages of the invention will become apparent as the specification proceeds.
- With the aforesaid objects in view, the invention consists of the novel combinations and arrangements of parts hereinafter described in their preferred embodiments, pointed out in the subjoined claims, and illustrated on the annexed drawing, wherein 40 like parts are designated by the same reference characters throughout the several views.
- Generally described, the article forming the subject of the present invention, consists of a pair of comparatively shallow and low 45 rimmed saucer-like elements, fitting in converted and inverted relation one inside of the other so as to constitute a powder box or receptacle. The lower element is formed, around its peripheral bottom corners, with
- an inwardly turned annular rabbet into which is crimped the free, depending edge of the rim of the upper element, in order to prevent these elements from being disassociated. The top of the upper element is provided with a flattened and depressed portion 55 having a central opening through which the powder is discharged. A gradually dished field reaches intermediate the circumferences of the depressed portion and the rim of the top element. At a specified distance from the inner edge of the discharge opening are formed in the depressed portion, a series of arcuate incisions or closed slits which serve to weaken the aforesaid edge and make it pliable or flexible. Coacting with the underside of the before mentioned edge of the discharge opening, is a closure member which is held up against the latter by means of a spring having differential resiliency. 60 Means are provided to limit the amount that the closure member may be depressed to admit of a certain outflow of powder from the receptacle, and also to make it more difficult or inconvenient to refill through the discharge opening. The power of the spring is sufficient to urge the receptacle elements apart and thus render them, as well as the closure member, inoperative, if an attempt 65 is made to pry open the crimped joint intermediate the said elements.
- The advantages of the invention as here outlined are best realized when all of its features and instrumentalities are combined in the one and same structure, but, useful devices may be produced embodying less 70 than the whole.
- It will be obvious to those skilled in the art to which the invention appertains, upon becoming conversant with the details thereof, that the same may be incorporated in 75 several different constructions. The accompanying drawing, therefore, is submitted merely as showing the preferred exemplification of the invention.
- In the said drawing:—
- 100 Figure I. is a full top plan view of this improved powder distributor;
- Fig. II is a section on the line II-II of Fig. I., looking upwardly in the direction of the thereto pertaining arrows;
- 105 Fig. III is also a top plan view of the article in question, from which some parts are omitted; and

Fig. IV is a fragmentary enlarged section of a detail, the section being taken on the line IV—IV of Fig. I, looking in the direction pointed out by the obliquely disposed 5 arrows.

In the form of the invention under consideration, the numeral "11" designates the lower one of a pair of preferably circular, substantially saucer-like shells or elements, and 10 comprises a bottom 13 and a low upstanding rim 15. The upper one 17 of the said elements includes a marginal annulus 19, and a rim 21 depending therefrom. This latter rim is of a size to take over the low rim 15 15 with a tight fit, on the order of a cover.

Below its marginal annulus the said upper shell 17, is provided in the middle thereof, with an approximately flat, depressed portion 23, the centre of which has cut therein 20 an opening 25. Intermediate the inner and outer circumferences of the annulus 19 and the said depressed portion, respectively, extends a sloping or funnel-shaped field 27. For the purpose of making the border of the 25 opening 25 yielding or flexible, so that it will accommodate itself tightly to the upper face of a closure member 29, the said portion is weakened transversely. This is conveniently accomplished by embodying on 30 the flat border or ledge 23, a series of incisions or indentations 31, in proximity to the said opening 25. By preference, these incisions may consist of a plurality of arcuate slits, spaced apart both endwise and 35 laterally, being as shown disposed in staggered arrangement with relation to one another. The slits are indicated by single lines in Fig. I, but in the enlarged disclosure afforded by Fig. IV, which is taken 40 across two of the aforesaid slits or incisions, it clearly appears that the metal between them, is forced downwardly or offset relatively to the plane it was originally situated in, still without severing the same from the 45 ledge. Subsequently to pressing the bridges or connecting strips 33 intermediate the before mentioned slits back into the normally flat position, as indicated in Fig. II, the opening 25 is punched out, so as not to 50 wrinkle or distort the interior edge thereof. While the treatment thus given to the flat edge or border 23, renders the same quite pliable, it does not permit any of the powder to leak through the incisions, in view of the 55 fact that their adjacent sides are ultimately in close contact with one another.

The hereinbefore named closure 29, is 60 preferably composed of a slightly crowned or convex disc-like plate surrounded by a downwardly curved peripheral border or edge 35. The edge last referred to, is held in abutting relation to the underside of the upper shell's flexible inner margin 23, by the outer ends of shorter and stiffer tongues 65 37 radiating from the central part of an astral-

shaped spring 39. The longer and more flexible tongues 41 of the latter, rest with their free extremities upon the bottom 13 of the lower shell 11 in proximity to its rim 15. At such times as the closure member 70 is depressed in order to discharge from the box or receptacle some of the powder contained therein, out through the opening 25 in the upper shell 17, for distribution over the ledge 23 and the sloping field 27 where it 75 can be mopped up by a powder-puff (not shown), the longer tongues 41 which are the lowermost as well, flex first, until an ear 43 touches the inside of the bottom 13. If the downward pressure is continued, the 80 higher located tongues 37 will also bend till the underside of the closure 29 strikes against another ear 45. Both of these ears, as seen to best advantage in Fig. III, are stamped out of the central part of the said 85 spring 39, and bent therefrom in opposite directions. The said ears 43 and 45 constitute stops for limiting the opening movement of the closure member relatively to the inner 90 marginal ledge 23. The construction of the 95 spring 39 is such that it not only holds up the closure, but guides the latter as well.

The means for preventing the container and cover elements 11 and 17 respectively, from being disassociated, comprise as indicated at the lower part of Fig. II and also in Fig. III, a rabbet 47 of a certain width, formed with the peripheral corners of the bottom 13 and the rim 15, which rabbet as shown, is turned inwardly of the shell 11. 100 The free or depending edge of the rim 21 pertaining to the cover shell 17 is, subsequently to the last named cover having been placed over its companion shell 11, crimped as represented at 49, into the said rabbet 47 105 from the underside. The interstice intervening between the inner circumferences of the rabbet and the crimped edge 49, may, as represented at 51, be filled with a suitable sealing material, in order to divulge to the purchaser of the article if the same has been 110 tampered with.

The spring 39 possesses ample strength to urge the shells 11 and 17 away one from the other, prior to the edge 49 being crimped 115 over the corner of the rabbet 47, so that if an attempt is made to turn over outwardly the said edge, for the purpose of recharging the bottom shell, the rims 15 and 21, of the latter and the cover shell, respectively, 120 cannot remain in tight association. Nor will, under the conditions mentioned, the closure 29 engage the ledge 23 with sufficient pressure to preclude leakage of powder therebetween, and therefore the article 125 is practically inoperative unless the shells 11 and 17 are intersealed. The average user of an article of this kind, does not possess appropriate implements for neatly taking apart and putting together the ele- 130

ments spoken of. Even a fairly good mechanician could only do this a few times before the edge 49 would crumble away under repeated bendings. Attempts to re-fill the assembled receptacle through its discharge opening, would be too tedious and inconvenient. Truly the space between the border 35 of the depressed closure and the overlying inner margin 23, is large enough to afford an outflow of powder when the box 10 lodged within a surrounding vanity case, is shaken or agitated. But this space is entirely too constricted to permit entering the powder therethrough, counterwise to 15 the air passing out of the receptacle which it has to replace. Matters would only be made worse by trying to tap or knock the box with the fingers or against some hard object, with a charge of powder deposited 20 on top of the closure, as this could only serve to stir up and cause the powder to fly about.

From the foregoing, it will be obvious that a practically non-refillable, inexpensive container has been devised, out of which the required amount of powder can be dispensed at will. The mere act of pressing down upon the closure thereof with a superposed powder-puff, while giving the container and its 25 encompassing casing, more or less of an accentuated shake, depending upon the quantity of powder therein, brings up enough of the latter for a facial application. Whenever the inter-sealed container shells are 30 emptied of their contents, they are discarded and a set of new and full ones is substituted 35 in their stead. When the article is to be filled from the beginning, the powder is poured into the lower shell 11 wherein the 40 spring 39 has previously been inserted. Subsequently, the closure 29 is laid upon the upper tongues 37 of the spring, after which the cover shell 11 is placed over the foregoing 45 assemblage, and finally sealed to prevent disassociation as hereinbefore described.

While a certain preferred embodiment of this device has been shown and described, it will be understood that changes in the form, arrangements, proportions, sizes and details 50 thereof may be made, without departing from the scope of the invention as defined by the appended claims.

Having described my invention what I desire to secure by Letters Patent and 55 claim, is:—

1. An article of the type specified, including a pair of coacting rimmed container elements, one of said elements being provided with a discharge opening in its top face, depressed below the rim of the other element, a spring urged closure coacting with the edge of said opening, and means for tightly securing the said elements one to the other to prevent disassociation and movement 60 therebetween.

2. An article of the type specified, including oppositely disposed rimmed container elements, one of said elements being provided with a discharge opening situated in a plane intermediate the outer and inner 70 limits of their respective rims, a closure controlling the discharge, a spring tending to spread apart said elements urging said closure against said opening, and means for fixing one element non-rotatably to the other 75 and preventing separation thereof against the action of said spring.

3. An article of the type specified, including rimmed shells placed in converted and inverted relation one inside of the other, 80 one of said shells having a discharge opening depressed both below the top thereof and the upper edge of the rim of the companion shell, a spring urged closure coacting with the edge of said opening, and means 85 for fixedly securing the rims of the said shells to one another to prevent disassociation thereof.

4. An article of the type specified, including a pair of container shells provided with 90 oppositely directed rims, the upper one of said shells having a discharge opening and its rim taking over that of the lower shell, said discharge opening being depressed below the edge of the rim of the last named 95 shell, a spring urged closure cooperating with said opening, and means for closely sealing the free edge of the outer rim near the bottom corner of the inner one to prevent rotation and disassociation of the said 100 shells.

5. An article of the type specified, including a rimmed container element formed with a rabbet near its bottom corner, a cover element having a discharge opening in its face 105 and provided with a rim taking over that of said container, and a closure coacting with said opening, the arrangement being such as to enable the free edge of the outer rim to be crimped into said rabbet to prevent the 110 said shells from becoming disassociated.

6. An article of the type specified, including a container element having a discharge opening in its upper face, means for increasing the resiliency of the inner margin 115 proper of said opening, and a spring urged closure coacting with said margin.

7. An article of the type specified, including an element provided with an opening, means for weakening the inner edge of said opening to enhance its yielding properties, and a closure adapted to be urged into coaction with said yielding edge.

8. An article of the type specified, including a container element provided with an opening in its surface, the inner edge of said opening having formed therewith a series of closed incisions capable of increasing the yieldability thereof, and a closure adapted to cooperate with said edge of the opening.

9. An article of the type specified, including an element formed with an opening, the edge of the latter being provided with staggered series of spaced but closed slits adapted to enhance its yieldability, and a closure coacting with said yieldable edge.
10. An article of the type specified, including a pair of associated container elements, one of the latter having formed therein a discharge opening, a spring urged closure coacting with the underside edge of said opening, and means for limiting the

movement of depression of said closure from said edge.

11. An article of the type specified, including associated elements forming a container, the upper one of said elements having a discharge opening therethrough, a closure cooperating with the under side edge around said opening, a spring urging said closure towards said edge, and means with said spring for limiting the opening movement of the closure.

HENRY C. KARLSON.
